UNITED STATES PATENT OFFICE.

WILLIAM A. HEMPHILL, OF PITTSBURG, PENNSYLVANIA.

ROLLER FOR FEED-TABLES.

SPECIFICATION forming part of Letters Patent No. 436,525, dated September 16, 1890.

Application filed June 19, 1890. Serial No. 355,924. (No model.)

To all whom it may concern:

Be it known that I, WILLIAM A. HEMPHILL, a citizen of the United States, residing at Pittsburg, in the county of Allegheny and 5 State of Pennsylvania, have invented or discovered a certain new and useful Improvement in Rollers for Feed-Tables, of which improvement the following is a specification.

The invention described herein relates to 10 certain improvements in that class of rollers employed in the feed-tables of rolling-mills and for other analogous purposes.

The object of this invention is to so construct these rollers that they shall be not only 15 light and durable, but also permit of a considerable reduction in the labor and cost of manufacturing them; and in general terms the invention consists in the construction and arrangement of parts, all as more fully herein- 20 after described and claimed.

In the accompanying drawings, forming a part of this specification, Figures 1 and 2 are 25 sectional elevations illustrative of the construction of such rollers heretofore in vogue. Figs. 3 and 4 are sectional and side elevations of my improved roller; and Fig. 5 is a trans- 30 verse section of the same, the plane of section being indicated by the line xx , Fig. 3.

These rollers have heretofore been con- 35 structed in many ways, the methods generally employed being illustrated in Figs. 1 and 2.

As illustrated in Fig. 1, the roller consists 40 of a cast-iron shell 1, having heads 2 2^a formed integral therewith. As cast-iron is easily fractured, it has been necessary to employ a wrought-iron and steel shaft 3, passing through suitable openings in the heads 2, and as these 45 rollers are generally driven, the opening in one of the heads, as 2^a , is made square in con- tour for the reception of a similarly-shaped portion on the shaft 3, thereby locking the roller and shaft together as against independent rotation. As will be readily understood, this fitting of the shaft and the opening in the

50 head involved considerable labor and added materially to the cost of production, and, further, the body of the roller being formed, as stated, of cast-iron, is easily broken by the heavy loads to which it is subjected. The 55 next step in the development of the art is

illustrated in Fig. 2, wherein the roller is shown as consisting of a wrought-iron shell riveted to flanges formed on cast-iron heads and a wrought-iron or steel shaft secured in the heads, as hereinbefore described. While 55 the wrought-iron shell rendered these rollers much more durable, the labor and cost of manufacturing them were greater than in the former case. In order to overcome these objections as to durability and cost of production, I form the roller with its end journals of 60 steel, by casting in a suitably-constructed mold.

As shown in Fig. 3, the roller consists of 65 the shell 1, provided with heads 2 at its opposite ends, said heads being in the form of central hubs provided with radiating arms connecting the hubs and the shell, as shown in Fig. 5, and the journals 4 at each end of the shell are formed integral with the hubs. 70 After the roller has been removed from the mold it is only necessary to remove the core, which can be readily done through the openings between the arms connecting the hubs and shell, face off the exterior of the shell, and turn 75 down the journals. These operations require but little skill and can be easily and readily effected. The rollers thus constructed of cast-steel can, by reason of the tenacity of the material employed, be made much lighter as regards the thickness of the shell and the arms 80 without any detriment to their durability.

It will be readily understood from the foregoing that the labor required in the manufacture of these rollers is much less than that 85 required in making either of the other forms, and consequently the cost of production is much less.

I claim herein as my invention—

A cast-steel roller consisting of a shell, hubs 90 connected by arms to the shell, and journals at the ends of the roller, said parts being formed integral with each other, substantially as set forth.

In testimony whereof I have hereunto set 95 my hand.

WILLIAM A. HEMPHILL.
